HEDGE TRIMMING DEVICE

Richard C. Johnsen, Hillside, N. J.

Application May 9, 1933, Serial No. 670,078

8 Claims. (Cl. 30—11)

This invention relates to hedge trimmers and particularly to electrically operated machines of this character.

An object of the invention is to provide an improved device which is light in weight, easily manipulated and can be manufactured at low cost.

A further object is to provide a device in which the drive is positive and properly balanced.

10 Other objects and advantages of the invention will appear from the following specification, reference being had to the accompanying drawing, in which like numerals denote like parts throughout.

15 Figure 1 is a view partly in section showing the front elevation of a device embodying the invention;

Figure 2 is a side elevation of the device in Figure 1, having a portion of the casing cut away;

Figure 3 is a view showing details of the drive mechanism of the device in Figure 1;

Figure 4 is a view on line A—A of Figure 3;

Figure 5 is a view on line B—B of Figure 2;

25 Figure 6 is an enlarged view of the cutter blade tensioning means.

In the embodiment illustrated, there is a main plate 10 and a cover plate 11 which are suitably shaped to form a support and casing for the operating mechanism. Main plate 10 and cover plate 11 have integral extended portions 12 and 13, respectively, having toothed formations 14 in one edge thereof. Extending portions 12 and 13 are so shaped that when brought together 30 and secured by bolts or rivets 15 they form a channel in which cutter or knife frame 16 is operably mounted and a slot 36 in which the cutter blade 17 is placed.

A power unit or motor 18 is mounted on main plate 10 and is provided with a shaft 19 extending into housing 20. A worm gear 20a is fixedly mounted on shaft 19 and is in mesh with gear 21, which in turn is fixedly mounted on shaft 22, rotatably disposed in housing 20.

45 On the opposite end of the shaft 22 is fixedly mounted eccentrically, two discs 23 and 23a which are in operable connection with connecting rods 24 and 25. Connecting rod 25 is pivoted by screw 26 to the rear end of cutter frame 16 and connecting rod 24 is pivoted to lever 27, at 28. Lever 27 is loosely journaled to link 29 by pin 30, link 29 being journaled to main plate 10 by screw 31.

50 The lever 27 has made integral therewith a gear segment 31 which is in mesh with the teeth

of rack 32 which is fixedly mounted on knife frame 16.

The cutting knife 17 can be made of flexible steel or other suitable metal, the cutting edge thereof being of suitable form as shown at 33, though any other suitable form may be used.

Cutting knife 17 being made of thin material has both of its ends bent in the form of a hook as shown at 34 and 35.

55 A slot 37 is provided in the rear end of frame 10 16 which slot is engaged by hook 34 of knife 17. At the opposite end of the frame is provided a tensioning means for knife 16 consisting of piece 38 having a slot 39 engaging hook 35 and an extended portion 40, which passes loosely through the upturned end of frame 16. Extended portion 40 has a slot 41 in its outer end to receive cam 42 which is held in position and rotates on pin 43.

A handle 44 is provided with a passageway 20 through which passes electrical conductors 45 for conveying current to motor 18. A switch 46 is provided in handle 44 whereby the current may be turned on and off as desired. A handle 47 is fixedly mounted on casing 10 for the proper 25 handling of the device.

From the foregoing description of the details of the device its operation is easily understood.

In operation conductors 45 are connected to some suitable source of electrical energy, the operator grasps handles 44 and 47, depresses switch 46 30 energizing motor 18, and causes it to rotate and in turn rotate worm 20a, gear 21, shaft 22 and eccentric disc 23, which through connecting rod 24 is operably connected to knife frame 16, causing it 35 to reciprocate.

To balance the moving parts of the mechanism, eccentric 23a is in operable connection through connecting rod 24, lever 27, gear segment 31 and rack 32 with knife frame 16, thus tending to maintain a balanced relation of the various moving parts. It is well understood that the device would be operable without the use of a second connecting rod and its associated parts, but by using these parts a smooth running and well balanced mechanism is obtained.

40 To compensate for the variable speeds of travel of connecting rods 24 and 25 during their cycle of operation, lever 27 is mounted on a movable fulcrum provided by link 29, which is free to swing within the limits fixed by pins 47a and 48. Knife frame 16 carrying with it knife 17 now being reciprocated rapidly in relation to the stationary toothed members between which it is placed, the hedge vegetation which may be in the space be- 45 50 55

tween the teeth is readily cut. The edges of the teeth being serrated tends to keep the vegetation from being forced away by the knife.

When it is desired to remove the knife from the device for sharpening or replacement, this can be readily done by swinging the handle of cam 42 to its reverse position, as shown by dotted lines. This releases the tension on the knife and it can be easily removed. To replace the knife, the reverse procedure is employed.

It may be desired to operate the device by other power means, such as a gas engine in which case the motor may be dispensed with and the mechanism driven by a flexible shaft connected directly to the engine.

While a preferred form of the invention has been illustrated and described, many changes can be made in the construction and arrangement of parts without departing from the scope of the invention as defined in the appended claims.

What is claimed is:

1. A hedge trimming device comprising a casing, said casing having integral extended portions forming a channel and tooth formations, said tooth formations being spaced apart, a knife frame within said channel supporting a flexible knife between said tooth formations, and means including a motor and a pair of lever rods connected thereto, one of said rods being pivotally connected to said knife, the other of said rods being linked to said casing.

2. A hedge trimming device comprising a casing, said casing having extended portions forming a channel and tooth formations, said tooth formations having serrated edges, a knife adjacent said tooth formations, and means including a motor and a pair of lever rods connected thereto, one of said rods being pivotally connected to said knife, the other of said rods being linked to said casing.

3. In a hedge trimming device, a casing having extended portions forming a channel, a knife frame mounted in said channel, an eccentrically mounted rotatable disc within said casing, a connecting rod in operable relation with said disc and said knife frame, a second eccentrically mounted rotatable disc, and a second connecting rod in operable relation with said second disc and through a lever and gear segments with said knife frame, said lever being mounted on a movable fulcrum secured to said casing.

4. A hedge trimming device having a casing, a knife frame supported by said casing, a flexible

knife mounted on said frame, means on said frame for holding said knife under fixed tension and means including a motor and a pair of lever rods connected thereto, one of said rods being pivotally connected to said knife, the other of said rods being linked to said casing.

5. A hedge trimming device, comprising an upper and a lower plate forming a casing, said plates having integral elongated portions forming a channel, said channel adapted to support a knife frame, a knife frame in said channel, a flexible knife supported under tension on said frame, and means mounted on said casing and means including a motor and a pair of lever rods connected thereto, one of said rods being pivotally connected to said knife, the other of said rods being linked to said casing.

6. In a hedge trimming device a casing, having extended portions forming a channel, a knife frame mounted in said channel, an eccentrically mounted rotatable disc within said casing, a connecting rod in operable relation with said disc and knife frame, a second eccentrically mounted rotatable disc, and a second connecting rod in operable relation to said second disc and through a lever and gear segments with said knife frame, said lever being mounted upon a fulcrum secured to said casing, said eccentric being mounted to operate 180° apart to actuate said connecting rods whereby said knife is caused to reciprocate by the alternate action of said rods.

7. A hedge trimming device comprising a casing, a knife adapted to reciprocate therein, and motor means for reciprocating said knife carried by said casing including a pair of levers one of said levers being connected to said motor means and pivoted on said knife, the other of said levers being connected to said motor means and to a link movably supported on said casing, whereby said knife may be reciprocated while said levers are in substantially balanced relation.

8. In a hedge trimming device, a casing having portions forming an extended channeled arm, a knife frame within said arm, a flexible knife mounted on said frame, means on said frame projecting outside said arm and casing for holding said knife under fixed tension, a motor on said support, and reciprocating means connected to said motor and extending to said frame for reciprocating the latter.

RICHARD C. JOHNSEN.
